DESIGN FOR AN EXERCISING SWING

Theodore D. Shumaker, Memphis, Tenn.

Application August 30, 1943, Serial No. 111,022

Term of patent 7 years

To all whom it may concern:

Be it known that I, Theodore D. Shumaker, a citizen of the United States of America, residing at Memphis, in the county of Shelby and State of Tennessee, have invented a new, original, and ornamental Design for Exercising Swings, of which the following is a specification, reference being had to the accompanying drawing, forming part thereof,

The figure is a perspective view of the exercising swing, showing my new design.

I claim:

The ornamental design for an exercising swing, substantially as shown.

THEODORE D. SHUMAKER.
